(57) **CLAIM**

The ornamental design for simulator enclosure, as shown and described.

DESCRIPTION

FIG. 1 is a rear perspective view of a simulator showing my new design invention;

FIG. 2 is a rear elevation view thereof;

FIG. 3 is a right side elevation view thereof, the opposite side being a mirror image thereof;

FIG. 4 is a top plan view thereof;

FIG. 5 is a bottom plan view thereof;

FIG. 6 is a front elevation view thereof; and,

FIG. 7 is a front perspective view thereof.

The broken line showing of simulator enclosure interior and supporting legs is included for illustration only and forms no part of the claimed design.
